United States Patent

Des. 241,464

Patented Sept. 14, 1976

241,464

EARRING

Morty S. Ravkind, Great Neck, N.Y., assignor to
Richton International Corporation

Filed June 23, 1975, Ser. No. 589,783

Term of patent 14 years

Int. Cl. D11—07

U.S. CL. D11—40

FIG. 1

FIG. 2

FIG. 3

FIG. 4

FIG. 5

FIG. 6

FIG. 1 is a front elevational view of an earring showing my new design;

FIG. 2 is a rear elevational view thereof;

FIG. 3 is an end elevational view looking from the left with respect to FIG. 1;

FIG. 4 is an end elevational view looking from the right with respect to FIG. 1;

FIG. 5 is a top plan view thereof; and

FIG. 6 is a bottom plan view thereof.

I claim:

The ornamental design for an earring, substantially as shown.
